UNITED STATES PATENT OFFICE.

JAMES W. TUCKER, OF CHICAGO, ILLINOIS.

GLAZIER'S INSTRUMENT.

No. 922,361.

Specification of Letters Patent.

Patented May 18, 1909.

Application filed April 22, 1908. Serial No. 428,506.

To all whom it may concern:

Be it known that I, JAMES W. TUCKER, a citizen of the United States, residing at Chicago, in the county of Cook and State of Illinois, have invented certain new and useful Improvements in Glaziers' Instruments, of which the following is a specification.

My invention relates to improvements in glaziers' instruments.

10 The object of this invention is to provide an improved construction in devices of this character.

It further designs to combine a cutter and oiler with a holder into which said cutter and oiler may be folded when not in use but which may be readily extended and brought into operative position.

20 To such end this invention consists in certain novel features of construction and arrangement, a description of which will be found in the following specification and the essential features of which will be more particularly set forth in the claims.

The invention is clearly illustrated in the 25 drawings furnished herewith in which—

Figure 1 is a perspective view of the device. Fig. 2 is a longitudinal section thereof. Fig. 3 is a perspective view of the wick holder. Fig. 4 is a detail section taken on 30 line 4—4 Fig. 2 and Fig. 5 is a cross-section of a slightly modified form of handle or casting.

In these views 10, is a handle preferably comprising two side plates 11, 11, connected 35 by a spring back 12 which is riveted or otherwise secured to the sides as shown at 13. This affords a combined handle and casing having an open side for the folding parts of the device. A wheel carrying blade 14, is 40 pivoted to one end of the handle by a pin, rivet or the like 15, and a wick holder 16 is pivoted to the other end of the handle by a pin, rivet or the like, 17. The wheel carrying blade and wick holder are each formed with 45 a shoulder 18, adapted to abut against the adjacent end of the spring back 12, after the manner of the ordinary knife-blade. The spring back also bears against projections 19 formed on the wheel carrying blade and wick holder respectively, to hold them in open or 50 closed position.

The end of the blade 14 is beveled off as at 20 and a cutter wheel or disk 21 is journaled in the angle formed at the extreme end of the 55 blade. The blade is forked at the end to receive the cutter wheel, and a screw 21' is se-

cured in the forked end to act as journal pin for the cutter wheel.

The wick holder is preferably in the form of a tube of rectangular cross section and contains a piece of wicking 22 which projects slightly beyond the end of the tube. This wicking may be made up of felt, gauze or other like absorbent material capable of retaining a quantity of oil or other lubricant, the object of which will appear later. Notches 23 are provided in the blade and holder to facilitate the opening out of the same. The blade and holder are so proportioned that when folded up the end of the wick will contact with the end of the cutter carrying blade, and wheel, thus automatically oiling the wheel and journal. The ordinary notches 24 may be formed in the blade after the manner of the ordinary glass cutter.

In Fig. 5 the handle is shown as made up of a single piece of sheet metal bent into a form having a U shape in cross section. This forms a simple and inexpensive handle and serves to contain the blade and holder when folded up. If desired the cutter wheel and wicking may be secured directly upon the ends of the handle thus dispensing with the folding blades.

Glaziers find it of great advantage to apply 85 oil along the line where the glass is to be cut and use a brush or other device for this purpose. I have found that by providing the cutting tool with an oiling device, considerable time and labor is saved, as the wick may 90 be dipped into the oil occasionally and drawn across the glass along the cutting line. Furthermore as the wick retains a considerable quantity of the oil, the cutter wheel and its journal are oiled by reason of their contact 95 with the wick when the blade and wick holder are folded up in the handle. The journal of the cutter wheel is thereby automatically oiled quite frequently and its durability is greatly increased. The screw connection affords means for the ready removal 100 of the cutter wheel whenever it becomes desirable to replace the same with a new one.

I am aware that various alterations and modifications of this device are possible 105 without departing from the spirit of my invention and I do not, therefore, desire to limit myself to the exact form shown and described.

I claim as new and desire to secure by Letters Patent:

1. A glazier's instrument comprising a

handle having a foldable tubular wick holder pivoted upon one end, and a wick in said holder extending beyond the end of said holder.

5. A glazier's instrument comprising an open sided handle having a cutter wheel blade pivoted upon one end and carrying a cutter wheel, and an oiler for said cutter wheel pivoted upon the other end, said blade 10 and oiler being adapted to be extended into operative position or folded up within the handle to bring the cutter wheel and oiler into engagement with each other.

3. A glazier's instrument comprising an open sided handle, having a cutter wheel blade pivoted upon one end, an oiler pivoted upon the other end, and a spring back for said handle engaging the blade and oiler to hold them either in operative or folded position, the blade and oiler being so proportioned and arranged that the oiler will apply 20 oil to the cutter wheel when the blade and oiler are folded up in the handle.

4. A glazier's instrument comprising an open sided handle having a cutter wheel blade pivoted upon one end, a tubular wick 25

holder pivoted upon the other end, and a wick confined in said holder and extending beyond the open end thereof and adapted to contact with the cutter wheel when the blade 30 and wick holder are folded up within the handle.

5. A glazier's instrument comprising an open sided handle, having a wheel carrying blade pivoted upon one end, a wick holder 35 pivoted upon the other end, and a wick confined in said holder, the blade and holder being so proportioned and arranged that the wick will contact with the cutter wheel when the blade and holder are folded up in the 40 handle.

6. A glazier's instrument comprising an open sided handle, having a foldable wheel carrying blade and a foldable wick holder, a cutter wheel journaled in said blade and a 45 wick in said holder, said wheel and wick being arranged to abut each other when the blade and holder are folded up within the handle.
